**DENTAL-PLAQUE-TRACING MEANS AND
METHOD FOR PREPARING THE SAME**

ABSTRACT OF THE DISCLOSURE

An expendable applicator for use in tracing dental plaque contains a predetermined amount of water-soluble dye. A method for preparing the applicator and the solution with which it is impregnated, is disclosed.

BACKGROUND OF THE INVENTION

The use of disclosing solutions containing a dye which serves to trace plaque deposits on the teeth has long been known. In Bender Pat. 2,151,495 it is suggested that a swab or brush may be dipped into a solution and while wet may be applied to the teeth. Dye-containing tablets which are to be chewed by the user and as exemplified by the Red-Cote tablet available from John O. Butler Co., Chicago, Ill. also have been used for this purpose. Moreover, various forms of dye including the use of fluorescent dyes in mouthwashes and the like and which are to be viewed with special light sources, as exemplified by Brilliant Pat. No. 3,309,274, have been suggested.

A practical problem, however, which so far as we know is common to all of these conventional practices, resides in the use of substantially more dye material than is required for an adequate degree of plaque tracing. The excess dye has to be disposed of by expectoration or rinsing from the mouth and may stain the surface of non-oral objects such as sinks, towels, clothing, or the skin. Unless promptly washed away, the dye may form a fixed stain particularly when the staining composition of matter includes adjuvants such as thickening agents, acid intensifiers and the like.

Although this disadvantage may prove to be only an annoyance when the plaque staining occurs in a dentist's office, it often is of such magnitude when the plaque staining is self-conducted in the home that use of this form of oral hygiene is soon discontinued. Such is especially true when children use the wet applicator, tablet or other means in which the dye is incorporated.

Moreover, the conscientious and continued self-checking of dental cleaning techniques, made possible by this staining concept, is made impractical by the inconvenience associated with currently available products.

SUMMARY

The invention is directed toward better practical oral care for dental patients who, upon being instructed in the plaque staining procedure and the subsequent proper teeth brushing technique, may then self-administer the dye by means of an improved applicator. In addition, this plaque staining applicator is particularly effective for use with children because the dye can be applied rapidly to tooth surfaces by the parent or by the child with parental supervision. The applicator includes a dry absorbent portion containing a predetermined amount of dye and surface active agent and which deposits the dye on the dental plaque while being wetted by saliva. An improved tracing solution with a formulation employing a reduced amount of dye is provided for impregnating the applicator, and the method for preparing the applicator includes the sat-

2

uration of the applicator followed by evaporation of the transfer agent used in the solution, and the drying of the applicator.

Among the objects of the invention are the provision of an improved dental-plaque-tracing solution, the provision of an improved method for preparing a dental applicator for tracing plaque; and the provision of a dry dental applicator containing a predetermined amount of dye and which is suitable for self-administration by the user. These and other objects of the invention will become more apparent as the description proceeds.

**DESCRIPTION OF THE PREFERRED
EMBODIMENT**

Dental plaque appears to be rather complex in its composition and its precise chemical nature is not known. In general, it comprises mucin, muco-polysaccharides, carbohydrate debris, and protein material of debris and bacteria. In the tracing of such plaque in accordance with this invention, it appears that both a physical and a physico-chemical action occur. In the former the dye can penetrate the plaque by capillary or osmotic action, while in the latter it can be loosely bonded to the plaque, depending upon the pH (acidity) in the mouth at the time of application, and with electrostatic forces holding the dye to the substrate.

The composition of the plaque moreover, appears to be lipoidal in natura and the interfacial tension between an aqueous dye solution and the lipid is quite high. Conventional staining solutions, therefore, have employed a relatively large amount of dye to circumvent this interfacial tension. As a result, excess staining of the entire oral cavity as well as non-oral objects normally results when these solutions with large dye percentages are used.

We now have discovered that by using a relatively small amount of surface active agent in the tracing composition, a significantly lower concentration of the dye can be employed with not only an economic gain from using less of the more expensive dye, but also a marked reduction in the unwanted staining of both oral non-plaque areas and the non-oral objects following use of the applicator.

The surface active agent, which may also be called a wetting agent, contains molecules which are both hydrophilic and lipophilic and the agent may generally be defined by its HLB number. This number signifies the hydrophilic-lipophilic-balance of the compound. The HLB numbers range from 0 to 20. The range of 10 to 16 is suitable in connection with the present invention. As an example Tween 80, a well-known product available from Atlas Powder Co., comprises essentially polyoxyethylene sorbitan monooleate. Use of more of such agent than is needed for adhering the dye to the plaque provides no advantage. We prefer, therefore, to use the surface active agent in an amount no greater by weight than that of the dye and preferably substantially less than the amount of dye.

The applicator construction may be of various forms without departing from the invention so long as it contains an absorbent portion having a predetermined dye holding capacity serving as a standard unit dosage. A preferred form of such applicator is of the Toothette type disclosed in Halford Pat. No. 2,667,655 and having a generally cylindrical absorbent portion comprised of polyurethane or other suitable copolymers and supported by a handle. The dye to be employed will, of course, be of an approved type for human usage and may be of various colors which are clearly visible under daylight or conventional artificial light. Water soluble dyes classified as xanthine dyes of the fluoran derivatives are suitable. For the purpose of transporting the dye from the bath of

solution to the absorbent portion of the applicator during impregnation of the applicator a conventional agent which will readily evaporate, preferably ethyl alcohol, is employed. Sweetening and flavoring agents are preferably included in applicators to enhance pharmaceutical acceptance.

The following specific examples are illustrative of the present invention.

EXAMPLE A

500 mg. of FD & C Red #2 dye in powdered form and 100 mg. of saccharin sodium are mixed with a small amount of distilled water to form a slurry. To this slurry 0.5 ml. of 1% aqueous solution polyoxyethylene sorbitan monooleate is added and intimately mixed. To this the flavoring agent is added and the final volume and concentration is adjusted with ethyl alcohol. The mixture is thoroughly stirred to form a homogeneous solution.

Into this solution a plurality of applicators are immersed and allowed to remain until the absorbent portion of the applicator is fully saturated. Excess solution is removed from the absorbent portion by constricting the saturated applicator uniformly through a tube thus to limit the amount of dye to that predetermined amount which the applicator can hold by true absorption. The applicator then is allowed to dry by evaporation of the alcohol leaving embedded in the absorbent material of the applicator, as a precipitate, the particles of dye coated with the surface active agent. Thereafter, the dry applicator is unit packaged and preferably is sterilized, as by treatment with ethylene oxide. As will be understood, the applicator normally will be thrown away following a single plaque tracing use.

EXAMPLE B

500 mg. of NM & R Red #2 dye in powdered form and 200 mg. of saccharin sodium, as a high concentration of sweetening agent, are mixed with a small amount of distilled water to form a slurry. To this slurry 1 ml. of a 1% aqueous solution of equal parts of Tween 20 and Tween 80 is added. The solution of surface active agents is intimately mixed with the dye-saccharin slurry. To this the flavoring agent is added and the final volume and concentration is adjusted with ethyl alcohol. The mixture is thoroughly stirred to form a homogeneous solution. Applicators were impregnated with this solution and then treated in the manner set forth in Example A.

EXAMPLE C

500 mg. of FD & C #3 dye in powdered form as a high concentration of dye and 100 mg. of saccharin sodium are mixed with a small amount of distilled water to form a slurry. To this slurry 0.5 ml. of 1% aqueous solution of polyoxyethylene sorbitan monooleate is added and

intimately mixed. To this the flavoring agent is added and the final volume and concentration is adjusted with ethyl alcohol. This mixture is thoroughly stirred to form a homogeneous solution. Applicators were then impregnated with this solution and treated in the manner set forth in Example A.

Upon being later used for tracing dental plaque, applicators made by the methods of each of Examples A, B, and C were found to be satisfactory.

10 As will be apparent to those skilled in the art, by choosing an applicator with an absorbent portion known to hold a predetermined amount of solution when fully saturated, and then preparing a solution having a desired dye content and fully saturating the applicator therein, applicators 15 made in accordance with these examples will be found to release sufficient dye to trace the plaque, but not to release excessive amounts of unneeded dye which might result in the disadvantages earlier mentioned. As will be understood, the dye is loosely held by the plaque and all 20 of the plaque is made clearly visible, after which the user by means of a conventional toothbrush may remove the plaque during the teeth cleaning operation. Even if by chance the plaque is not entirely removed the water soluble dye will soon disappear.

25 In view of the above disclosure, it will be noted that the several objectives of the invention are achieved and other advantageous results obtained.

What is claimed is:

30 1. A dry single-use, throwaway-type handle-supported dental plaque-tracing applicator including an absorbent portion containing a predetermined amount of dental plaque tracing composition comprising a water-soluble dye and a surface active agent, the absorbent portion of said applicator being adapted to deposit said dye upon 35 dental plaque during contact with the teeth and while being wetted by saliva.

40 2. An applicator as defined in claim 1 wherein said composition includes a sweetening agent and a flavoring agent in an amount sufficient to mask the taste of said surface active agent and enhance pharmaceutical acceptance.

45 3. An applicator as defined in claim 1 wherein said composition contains less of said surface active agent than of said dye, measured by weight.
